UNITED STATES PATENT OFFICE.

GEORGE SAMUEL KENT, OF BUFFALO, NEW YORK.

BOILER-FURNACE.

1,312,185.

Specification of Letters Patent.

Patented Aug. 5, 1919.

Application filed October 19, 1916. Serial No. 126,491.

To all whom it may concern:

Be it known that I, GEORGE S. KENT, a citizen of the United States, residing at Buffalo, in the county of Erie and State of New York, have invented a new and useful Improvement in Boiler-Furnaces, of which the following is a specification.

This invention relates to furnaces of the kind which are used in connection with steam boilers and in which the draft passes first through the green fuel and then through the hotter parts of the fuel.

The object of the invention is to provide a furnace of this kind having a single fire place in which the fire or burning fuel is confined by means of water bars or tubes arranged at the sides of the burning fuel and between which the products of combustion pass to opposite sides of the fire or fuel; also to provide a furnace structure in which the water bars or tubes can be easily removed and replaced; also to improve the construction of the water bars and the manner of placing the bars into their operative positions in the furnace; also to construct the parts of the furnace in such a manner as to support the fire or burning fuel to a certain extent independently of the grate bars, to facilitate the removing of clinkers or the like; also to improve the arrangement of the fuel door of the furnace in such a manner as to enable the same to distribute the draft or incoming air uniformly over the fire; also to improve the construction of furnaces of this kind in other respects hereinafter specified.

In the accompanying drawings:

Figure 1 is a front elevation of a boiler furnace embodying the invention.

Fig. 2 is a fragmentary, central, longitudinal sectional elevation thereof.

Fig. 3 is a longitudinal, sectional, elevation on line 3—3, Fig. 4.

Fig. 4 is a front elevation of the boiler furnace embodying the invention, having the front wall of the furnace removed.

Fig. 5 is a detailed view, on an enlarged scale, of a water bar or tube showing the connections with the upper and lower headers.

Fig. 6 is a transverse, sectional, elevation of one of the upper headers of the furnace, showing the joint between the boiler and the header.

A represents a boiler of any usual or suit-

able construction, that shown having fire tubes *a* through which the products of combustion pass from the rear to the front of the boiler. The boiler and furnace are enclosed in the usual manner, for example, by means of side walls *a'*, a rear wall *a²* and upper and lower front walls or plates *a³* *a⁴*. The housing of the boiler also includes the usual fire wall *a⁵* which extends from side to side of the boiler housing and which causes the hot products of combustion to pass upwardly over the wall in proximity to the boiler. All of these parts may be of any suitable or usual construction.

The furnace, which is arranged under the boiler, consists of a central fire chamber *B* and an ash pit *b* arranged under the fire chamber and separated therefrom by means of a grate *b'*. The fire is confined within the fire chamber by means of a plurality of water bars or pipes *C* arranged in rows at opposite sides of the fire chamber, the water bars or pipes being spaced at short intervals from each other so as to leave spaces between the bars through which the gases of combustion can pass. The upper rear end of the fire chamber is closed by means of a wall *b²* projecting above the fire wall *a⁵* which causes the air which is admitted to the fire chamber above the fuel to pass downwardly first through the green fuel, then down through the hot portions of the fuel and out of the fire chamber between the water bars. The gases of combustion then pass over the fire wall and through the fire tubes of the boiler to the chimney.

The water bars are secured at their upper ends in headers *D* and at their lower ends in headers *E*, each of the headers preferably consisting of a single hollow bar extending lengthwise of the boiler. The upper headers *D* are connected by means of tubes or pipes *d* with the boiler, the connection being preferably made near the upper portion of the boiler. In the construction shown, the pipes *d* are connected at their upper ends with the boiler by removing two of the fire tubes *a* and utilizing the hole in the boiler thus formed to connect the upper ends of the pipes *d* with the boiler. The upper headers *D* are preferably constructed as follows:

Each of the upper headers *D* consists of a long, hollow bar, preferably made of cast steel, and resting at its rear end on the fire

wall a^5 and having its front end embedded in and supported by the front wall of the boiler. Each header has an upper body portion d' , Fig. 6, and a lateral extension or hollow flange d^2 to which the water bars of the furnace are secured. In order to secure the water bars in the lateral extensions of the headers, the extensions are provided with holes d^3 through which the water bars 10 or tubes can be passed, and holes d^4 at the opposite side of the lateral extension which are substantially in alinement with the holes d^3 through which the water bars pass and which are adapted to be closed by means of 15 plugs or the like d^5 . A tube or water bar when inserted through the hole d^3 in the extension is permanently secured to the header in the usual manner by means of an expanding tool or the like, not shown, which may be passed through the hole d^4 . d^6 represents 20 stay rods or parts which are preferably cast integral with the side walls of the upper water headers for the purpose of preventing the pressure of the steam from forcing these 25 side walls outwardly.

The upper wall of each water header D is preferably made to rest against the underside of the boiler and is provided with a shallow groove or depression d^7 extending 30 lengthwise thereof, which is filled with some suitable fire resisting packing, such as asbestos or the like, which forms a substantially air-tight joint between the headers and the boiler, so that any air passing over the fire 35 is forced to pass downwardly to the fire and cannot escape between the upper headers and the boiler. Any other means may be provided for making a tight joint between the upper headers and the boiler.

40 The lower headers are constructed in substantially the same manner as the upper header, each comprising a body portion e and a lateral extension or hollow flange e' provided with holes e^2 for the lower ends of 45 the water bars C and holes e^3 in alinement with the holes e^2 and adapted to be closed by means of plugs or screw caps e^4 . The lower headers are also provided with stay rods or members e^5 . The lower faces 50 of the headers are arranged, in the construction shown, to rest upon tiers or supports e^6 , so that these tiers together with the body portions of the lower headers form the side walls of the ash pit.

55 In order to secure the water bars or tubes to the upper and lower headers, each of the tubes C is preferably made in two parts, an upper part c and a lower part c' the two parts being welded together at their meeting edges, as shown at c^2 . By means of this 60 structure the holes d^3 and e^2 in the upper and lower headers can be drilled in such a manner that the water bars fit accurately into the same. In placing the two parts of 65 the water bar in position, either the upper

or lower part is first inserted into the hole in the corresponding header and enters into the hole to a sufficient extent to permit the other part of the water bar to be placed into the corresponding hole in the header in a 70 direction parallel with the axis of the hole. The two adjacent ends of the water bar are then brought together and welded, after which the ends of the water bar may be secured in the headers. By means of this 75 structure the repairing of the furnace is greatly facilitated, since a defective water bar can be taken out and replaced by a new one without requiring any of the parts of the furnace, with the exception of the plugs 80 or caps d^5 e^4 , to be removed from the furnace.

The feed water for the boiler is preferably fed first to the lower header and then passes upwardly through the water bars 85 into the upper header and into the boiler. In the arrangement shown in the drawings, the feed water enters the boiler through a pipe or passage f which terminates in two drums or containers F arranged at the sides 90 of the ash pit, in which drums the solid matter in the feed water is given a chance to settle. The mud drums are connected to the lower headers by means of pipes or tubes f' . The rear ends of the mud drums are preferably connected with the bottom of the boiler by means of pipes f^2 through which sediment from the boiler can pass into the mud drums. Each mud drum is provided with a blow-off pipe f^3 through which the drum 100 can be cleaned by draining or blowing off the sediment collected therein. Other suitable connections between the mud drums and the boiler and furnace may be provided.

The front wall of the boiler may be made 105 of unitary structure or it may be made in two parts a^3 and a^4 as shown, the two-part construction being preferably employed in case the furnace is installed under an old boiler, since then the front wall or plate in 110 the case of an old boiler can be cut so that the upper portion of the old front wall of the boiler need not be interfered with. The lower portion of the front plate of the boiler is provided with a feed or fuel door G, the 115 usual ash pit door g and man holes g' g^2 and g^3 which afford access to the various parts of the furnace. All of these parts may be of any suitable or usual construction. The feed door of the boiler is preferably made 120 as shown in Figs. 1 and 2 and is pivoted on hinges g^4 in such a manner as to swing upwardly when opened. The supply of air to the fire in the furnace shown is admitted 125 through the feed door and by pivoting the feed door to swing vertically, the draft is uniformly distributed over the fire. In case of a feed door which is hinged to swing side- 130 wise, the draft would be directed more toward one side of the furnace than toward

the other and would cause an uneven burning of the fuel. Furnace doors of other suitable constructions may, however, be employed if desired.

- 5 The upper headers of the furnace are preferably so arranged that the flanges or extensions d^2 extend inwardly toward each other, as shown, and the extensions or flanges of the lower headers may be turned outwardly 10 so that the water bars connecting the flanges of the headers incline downwardly and outwardly. By means of this arrangement the fire which is so arranged that the fuel at the top of the fire is located above the lower 15 portions of the headers forms an arch or bridge over the space between the lateral flanges in such a manner that the mass or cake of burning coal is more or less supported by the flanges. Consequently, the removing of a clinker or the like from the 20 grate bars at the lower portions of the fire chamber is greatly facilitated. The arch or bridge formed by the fire across the flanges of the upper headers can be easily broken 25 down when desired.

In the operation of the furnace the gases pass downwardly through the fire so that the gases from the green fuel pass through the glowing embers and are completely 30 burned so that no smoke is produced by the fire in the furnace. The water entering into the boiler passes through the headers and the water bars which are exposed directly to the heat of the fire so that a considerable 35 amount of heat is imparted to the water before passing to the boiler. The furnace construction not only utilizes to the best advantage the heat produced by the fire but also produces a fire of intense heat and one 40 in which the smoke is consumed. The furnace construction is described as applied to a single furnace arranged centrally under a boiler, but it will be understood that it is not intended to limit the invention to this 45 arrangement nor to the number of fire places which may be arranged under a boiler. The drawings show a structure in which both side walls of the fire chamber are composed of water bars, but if desired, one side wall 50 of the fire chamber may be of other suitable structure than that shown.

I claim as my invention:—

1. The combination with a boiler, of a furnace arranged under the boiler, a plurality of substantially upright water bars spaced at intervals and forming the sides of said furnace, water headers with which the upper ends of said bars connect and which are arranged in engagement with said boiler and extend downwardly from the boiler to form the upper portions of the sides of said furnace, means for admitting air to the furnace into the space between said headers, and connections for permitting water to flow from 65 said headers to said boiler.

2. The combination with a boiler, of a furnace arranged under the boiler, a plurality of substantially upright water bars spaced at intervals and forming the sides of the furnace, water headers arranged in engagement with said boiler to form substantially air tight connections therewith and having flanges extending inwardly with regard to said furnace and means for admitting air to the furnace into the space between said headers, said water bars being connected to said flanges, and connections for permitting water to flow from said boiler to said headers. 70 75

3. A furnace including a grate, a plurality of water bars extending upwardly from said grate and forming a retaining wall for a fire chamber, said water bars being spaced at intervals to permit gases to pass through the spaces between the bars, and a header 80 85 forming the upper end of the furnace wall and having a hollow integral flange extending inwardly with regard to the furnace to form a support for fuel and to which the upper ends of the water bars are connected, 90 said flange having holes through which the water bars may be removed from the furnace.

4. The combination with a boiler, of a furnace arranged below said boiler and comprising a grate, water bars arranged in operative relation to the grate and forming retaining means for the fire, said water bars being arranged at intervals forming spaces 95 through which the gases of combustion can 100 pass, headers which consist of hollow bars of unitary structure extending lengthwise of the furnace and forming a substantially air tight connection with said boiler and with which the water bars are connected and 105 which form with said boiler a space through which air is admitted to the fire chamber above the fire, and connections for permitting water to flow between said header and said boiler. 110

5. The combination with a boiler, of a furnace arranged under the boiler and including a grate, water bars extending upwardly from the grate and arranged at intervals forming spaces for the passage of 115 gases, water headers at opposite sides of said furnace with which the upper ends of said bars connect, said headers being arranged in engagement with the boiler and forming substantially air tight connections therewith, and connections for permitting water to flow from said header to said boiler. 120

6. The combination with a boiler, of a furnace arranged under the boiler and including a grate, water bars extending upwardly from the grate and arranged at intervals forming spaces for the passage of 125 gases, a water header with which the upper ends of said bars connect, said header being arranged in engagement with the boiler and 130

having a longitudinal groove, packing in said groove forming a substantially air tight joint between said header and said boiler, means for admitting air to the furnace into the space between said headers, and connections for permitting water to flow from said header to said boiler.

7. A furnace including a grate, a plurality of water bars extending upwardly from said 10 grate and forming a retaining wall for a fire chamber, said water bars being spaced at intervals to permit gases to pass through the spaces between the bars, and a header having a hollow flange which extends inwardly with regard to said furnace to form 15 a support for fuel and which is provided with holes in its lower wall through which the upper ends of the water bars extend, and holes in the upper wall of said flange arranged opposite to the ends of said water bars through which access may be had to the 20 water bars, and means for closing said holes in the upper wall of the flange.

8. The combination with a boiler, of a 25 furnace arranged under the boiler, a plurality of substantially upright water bars spaced at intervals and forming the sides of said furnace, water headers with which the upper ends of said bars connect and which 30 are arranged in engagement with said boiler to extend downwardly from the boiler to form the upper portions of the sides of the furnace, said headers forming with said 35 boiler a passage in the upper part of the furnace and below said boiler for fresh air to pass to the fire, means for admitting air to said passage, and connections for permitting water to flow from said boiler to said 40 headers and water bars.

9. A furnace comprising upper and lower headers arranged at the upper and lower

portions of the furnace and having laterally extending flanges provided with oppositely disposed holes, water bars secured at their upper ends in the holes of the upper header 45 and at their lower ends in the holes in the lower header, openings in said flanges arranged opposite to said holes whereby access can be had to said bars and whereby parts of the water bars can be inserted into or removed from their operative positions, and means for closing said openings.

10. A furnace comprising upper and lower headers arranged at the upper and lower portions of the furnace and having laterally extending flanges provided with oppositely disposed holes, water bars, each consisting of two parts, one part extending into a hole in the upper header, the other part extending into a hole in the lower header, the two parts being welded together and secured in said holes.

11. A furnace comprising upper and lower headers arranged at the upper and lower portions of the furnace, water bars each consisting of two parts, one part extending into a hole in the upper header and the other part extending into a hole in the lower header, said headers having holes arranged substantially in alinement with said water bars and opposite to said first mentioned holes through which said water bars may extend when placing the same into or removing them from the headers, the two parts of the water bars being welded together and secured in said first mentioned holes.

Witness my hand this 17 day of October, 1916.

GEORGE SAMUEL KENT.
